INTERNAL COMBUSTION ENGINE

Ludger E. La Brie, South Bend, Ind., assignor to
 Bendix Aviation Corporation, South Bend, Ind.,
 a corporation of Delaware

Application May 2, 1931, Serial No. 534,541

6 Claims. (Cl. 123—79)

This invention relates to internal combustion engines and more particularly to valve mechanisms therefor.

An object of the invention is to provide a valve mechanism for an internal combustion engine that will permit the engine to operate with a high volumetric efficiency.

Another object of the invention is to provide a valve mechanism that is quiet in operation and has a rapid opening movement.

Another object of the invention is to provide a valve mechanism in which a rapid rate of opening is secured without imposing a high rate of acceleration to the valve parts.

Another object of the invention is to project the valve parts into the cylinder during the intake period and direct the gas into the engine cylinder at a substantial distance from the end wall of the cylinder. It is the desideratum of valve mechanisms for internal combustion engines that they be quiet in operation and have a high rate of opening speed. These two qualifications are somewhat antagonistic in their attainment, and the rate of valve opening is usually selected as a compromise with the noise characteristics. It is desirable to have a rapid opening, for otherwise the average opening is so small with respect to the maximum opening that it may be necessary to increase the size or lift to obtain satisfactory engine results.

With the above objects and difficulties in mind, the present invention preferably comprises a pair of relatively movable valve parts arranged to be individually operated in timed relation.

A feature of the invention relates to the mounting of a poppet valve within a reciprocating valve sleeve having communication with the engine intake ports and an operating means that actuates the valve and sleeve concurrently for a short period, then separates them by opposite movements, and finally closes the valve with both sleeve and valve moving in the same direction.

A better understanding of the invention may be obtained by referring to the accompanying drawings in which I have illustrated certain embodiments of the invention and in which:

Figure 1 is a sectional view of the head portion of an internal combustion engine illustrating my improved valve operating mechanism;

Figure 2 is a view of the valve operating mechanism taken in the direction of the arrows 2—2 in Figure 1;

Figure 3 is a modified form of the invention;

Figure 4 is a view taken in the direction of the arrows 4—4 of Figure 3;

Figure 5 is a diagrammatic view of the movement of an intake valve which is operated by my improved valve mechanism;

Figure 6 is a diagrammatic view illustrating the movement of my improved valve mechanism as applied to the exhaust valve of an internal combustion engine.

Referring to the forms shown in Figures 1 and 2, 10 is an engine cylinder having a head 11 and provided with a spark plug 12 and water spaces 13. Fuel is supplied to the cylinder 10 through an inlet manifold 14 which communicates with port 16 in reciprocating sleeve 17, the outlet of which is closed by poppet valve 18. Sleeve 17 is provided with a valve seat on its outer end and is slidably mounted in head 11 and is normally urged upwardly against shoulder 17' by a spring 20 which coacts between nut 19 and shoulder 21, the sleeve being restrained against rotary movement by split washer 22, which is pinned or otherwise secured to the head and has inwardly projecting tongues extending through the slots 24, formed in sleeve 17. Poppet valve 18 is slidably mounted in a guide member 26, secured within sleeve 17 and is urged upwardly into seating contact with the outer or seating end of sleeve 17 by a spring 27 which coacts between washer 28 and the shouldered portion 29 of the guide. Both sleeve 17 and valve 18 are actuated by a cam shaft 31 having cams 32 and 33, each of which operates respectively, rocker arms 34 and 36, which contact respectively with the sleeve and valve through adjusting screws 37 and 38. Cam shaft 31 is driven through any desired operating means (not shown), in timed relation with the engine, and rocker arms 34 and 36 are pivotally supported at 39 upon the head 11. The operating mechanism shown may be also used with an exhaust valve, the operation of which is understood by those skilled in the art and need not be described herein, except to say that the operation is the same except for the different timed relation with respect to the engine as shown in the diagrammatic view, Figure 6.

In the operation of the engine, cam shaft 31 is rotated in a clockwise direction and both valve and sleeve are reciprocated downwardly from point A to point B in Figure 5, the opening slope of the cams being preferably identical in form, although care should be taken to see that adjusting screw 38 is so positioned as to allow a slight clearance between the screw and valve stem 41 to insure seating of the valve upon the sleeve 17 during the movement from A to B.

From point B to point C, sleeve 17 is moved upwardly by spring 20 and valve 18 continues its downward movement to point C, whereat it starts its upward movement, and both valve and the seat on the sleeve are closed simultaneously at point D. It may be seen that due to the opposite movements of the sleeve and valve from point B to C, the rate of opening movement is very rapid and enables the gas to enter the cylinder with less resistance than is imposed by the ordinary valve mechanism, thus insuring a high volumetric efficiency. The same rate of opening as is obtained by my improved valve mechanism may possibly be secured by the conventional valve and operating cam, but the slope of the cam surface in the conventional construction would have to be designed much steeper than the one that I am able to use with the present mechanism, and the result would be a very noisy valve mechanism, such as is used in racing cars.

In the diagrammatic view illustrated in Figure 5, I have shown the movement of the valve during one revolution of the engine, which includes the intake cycle. The cross-hatched portion from A to B of the outer circle, represents movement of the parts corresponding to the movement of cam shaft 31 in Figure 1, during which both valve and sleeve are moving downwardly. The solid portion of the outer circle from B to D represents the angular movement during which valve 18 is separated from the seat on the sleeve 17 and corresponds to the conventional inlet diagram. Valve 18 starts to close at point C and both valve and the seat on the sleeve close simultaneously at point D. The cross-hatched portion of the inner circle from B' to C' represents the time during which valve and sleeve are moving in opposite directions and the solid portion from C' to D' represents slow movement of the sleeve during the last portion of its travel toward its closed position.

In the diagrammatic showing of Figure 6, I have illustrated the movement of the sleeve and valve as applied to the exhaust valve of an engine and the corresponding portions of the figures are analogous to the inlet diagram shown in Figure 5.

In the forms shown in Figures 3 and 4, I have eliminated the rocker arm construction and have shown an overhead cam shaft 51 having cams 52 and 53. Cam 53 bears on the sleeve 17 through the medium of a rocker arm 55, pivotally mounted on the head at 56, and cam 52 bears directly on thrust collar 57 secured to the outer end of valve 18. A guide screw 59 has an extension 60 projecting through slot 61 in sleeve 17 for preventing rotation of the sleeve and misalignment of port 63 with the manifold 64.

In each of the constructions shown, sleeve 17 seats against a shouldered member 11 forming a pocket wherein gases or lubricant may collect to cushion the fitting of the sleeve, but if desired, a venting slot 67 may be provided for permitting gases or lubricant to be forced out of the pocket and into the intake manifold.

It may be noted from the above description that I have provided a valve mechanism having a very rapid opening and a cam slope that will not unduly accelerate the parts, and in which the seating of the valve upon the sleeve occurs while both sleeve and valve are moving in the same direction at different rates of speed, thereby insuring quiet operation of the valve with a high rate of opening speed.

While I have illustrated and described certain embodiments of my invention, it is understood that this showing and description are illustrative only, and that I do not regard the invention as limited to the forms shown and described, or otherwise, except by the terms of the following claims.

I claim:

1. In an internal combustion engine, a valve mechanism comprising, a sleeve having a valve seat on its outer end, a poppet valve coaxial therewith, means to move the sleeve and valve concurrently for a portion of the valve travel, means to separate the valve and sleeve valve seat, and means to return the valve and sleeve concurrently to their inoperative positions.

2. In an internal combustion engine, a valve mechanism comprising, a sleeve having a valve seat on its outer end, a poppet valve coaxial therewith, means to move the sleeve and valve concurrently for a portion of the valve travel, means to simultaneously move the valve and sleeve in opposite directions, means to return the valve and sleeve concurrently to their inoperative positions, and a stop for limiting the return movement of the sleeve.

3. In an internal combustion engine, a valve mechanism comprising, a spring loaded sleeve having a valve seat on its outer end, a spring loaded valve coaxial therewith, and separate cam means for actuating said sleeve with valve seat and valve to open the valve by moving the sleeve oppositely to the valve.

4. In an internal combustion engine, a valve mechanism comprising, a spring loaded sleeve with valve seat, a spring loaded valve coaxial therewith, and separate cam means for actuating said sleeve and valve seat and valve to close the valve while the sleeve is moving in the same direction as the valve.

5. In an internal combustion engine, a valve mechanism comprising two reciprocating members coacting to form a valve closure, means for separating said members during their movement, and said means being arranged to move said members in opposite directions during the separation period.

6. In an internal combustion engine, a valve mechanism comprising, a sleeve having a valve seat on its outer end and a coaxial poppet valve, means for separating said sleeve valve seat and valve during their movement, and said means being arranged to move said sleeve and valve in opposite directions during the separation period.

LUDGER E. LA BRIE.
